UNITED STATES PATENT OFFICE.

CAROLINE W. MCKINLAY, OF WESTPORT, WASHINGTON

DESIGN FOR A TOY.

49,617.

Specification for Design.

Patented Sept. 5, 1916.

Application filed May 5, 1916. Serial No. 95,718. Term of patent 14 years.

To all whom it may concern:

Be it known that I, CAROLINE W. MCKINLAY, a citizen of the United States, residing at Westport, in the county of Grays Harbor and State of Washington, have invented a new, original, and ornamental Design for a Toy, of which the following is a specification, reference being had to the accompanying drawing, forming part thereof.

Figure 1 is a perspective view of the toy

looking toward the head and from one side, and Fig. 2 is a perspective view looking from the rear and from one side.

I claim:

The ornamental design for a toy, as shown.

CAROLINE W. MCKINLAY.

Witnesses:

MARY SMITS,
RALPH WILLEY.
